UNITED STATES PATENT OFFICE

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

CAR-COUPLER MECHANISM

Application filed February 11, 1929. Serial No. 339,116.

My invention relates to car couplers and particularly to those in which the lock for restraining outward rotation of the knuckle is designed for bottom operation. The invention is especially suitable for cooperation with the locking mechanism of the Standard "D" type coupler. The principal object of the invention is to provide, as a rigid part of the coupler head, a coupler supporting means upon which is mounted release mechanism for actuating bottom operated locking mechanism of a car coupler. A further object of the invention is to construct the coupler support so that, without impairing its strength, it may form a mounting for a coupler release rigging. A still further object of the invention is to form the coupler support in such manner that a particular type of coupler release rigging may be readily mounted thereon.

Where freight cars and locomotive tenders are provided with car couplers which are adapted to yield longitudinally of the car in draft and buffing, it is the present general practice to locate the coupler carrier a sufficient distance to the rear of the coupler head to permit the coupler to perform its full buffering travel, with a safe allowance to provide the added clearance which wear of parts makes necessary. It is also common practice to support a short shank pivoted pilot coupler by a pocket flange casting, the point of support of the coupler being to the rear of the coupler head. As these points of support are considerably to the rear of the center of gravity of the coupler its head tends to droop. This drooping increases as wear of the parts proceeds. Not only is the flexibility for vertical and horizontal angling between mating couplers thereby reduced, but the proper operating relationship between the coupler lock and the uncoupling mechanism is detrimentally affected in those cases in which the lock operating devices are mounted upon the car, tender or locomotive, thus decreasing the efficiency of operation of the lock actuating devices. Both of these undesirable results are avoided by the present invention.

The principal feature of the invention, generally stated, consists in providing the rail-

way vehicle with a coupler carrier which extends under and is adapted to cooperate with a member rigidly attached to and projecting downwardly from the underside of the coupler head, and in associating therewith coupler lock operating mechanism which is movably mounted upon said downwardly projecting member at a point above the coupler carrier.

Other features of the invention pertaining to particular combinations and advantageous details of construction will herein-after appear and be pointed out in the claims.

In the drawings:

Figure 1 is a side elevational view of a car coupler mechanism embodying the invention, showing its relation to the coupler carrier and adjacent parts of the car structure, the carrier and car structure being in vertical central section and the coupler lock being in locked position.

Figure 2 is a sectional view on the line 2—2, Figure 1, the coupler release mechanism being omitted and portions of the coupler being shown in dot and dash lines.

Figure 3 is a front elevational view of the construction shown in Figures 1 and 2, portions of the car coupler being broken away.

Figure 4 is a detail view, partly in side elevation and partly in section showing the relations assumed by the parts when the coupler release mechanism is being assembled with or disassembled from the coupler lock.

Figure 5 is a view corresponding to Figure 4, but illustrating another step in the operation of assembly or disassembly of the mechanism.

Figure 6 is a detail rear elevational view of a portion of the combined coupler support and release rigging mounting.

Figure 7 is a detail view of the side elevation illustrating the application of the invention to a short shank pilot coupler.

The construction shown in the drawings is especially suitable for embodiment in a car coupler mechanism having a head 1 and bottom operating lock 2 which are of the well-known Standard "D" type. Rigidly connected to the coupler head, preferably by being cast as an integral part thereof, is a coupler

support 3 whose lower end slidably bears upon a coupler carrier 4. The coupler carrier, which is rigidly connected to the railway vehicle, may be, and preferably is, provided with a removable wear plate 5 which directly engages the lower end of the columnar supporting member 3. As shown in the drawings the coupler carrier 4 may advantageously be formed as a transversely extending bar having upwardly projecting flanges 6 which are spaced longitudinally of the coupler so as to receive between them the downwardly projecting flanges 7 of the coupler carrier wear plate 5. The flanges 6 and 7 respectively serve to stiffen the carrier and its wear plate portion. For rigidly connecting it to the railway vehicle, the transversely extending channel-shaped bar of the coupler carrier by which the wear plate 5 is supported at its opposite ends with rearwardly and upwardly extending arms 8 spaced laterally a distance sufficient to afford clearance for the downwardly projecting coupler support 3 in all positions the coupler may assume in normal service. The arms 8 are preferably of curved form and may advantageously diverge rearwardly. Each may be provided with an outwardly extending lug 9 permitting it to be riveted to the adjacent car sill 10 and they may be transversely braced toward their upper ends by an integral tie bar 11. To provide lateral stiffness, the arms 8 are preferably fashioned with inwardly projecting flanges 12 which extend from the tie bar 11 to the inner vertically extending flange 6 of the coupler carrier. As shown in Figures 1 to 6 inclusive of the drawings, the coupler carrier may be formed as an integral part of an end casting or striking plate 13 having an opening therein through which the shank 14 of the car coupler projects.

The coupler support 3 which projects downwardly from the underside of the coupler head is preferably formed with a vertically extending columnar portion 15 of plate-like form to the lower end of which a horizontal pad or wear pad 16 of general rectangular form is integrally united. The end of the pad 16 preferably projects rearwardly beyond the coupler head and when the coupler is in normal position overhangs the wear plate 5 of the coupler carrier both fore and aft for a distance sufficient to afford ample bearing against the member 5 in all positions the coupler may occupy in service. By this means the coupler carrier may be reduced in size and compactness of the device is effected.

The vertically extending plate-like portion 15 of the coupler support 3 is preferably of angular form, having a longitudinally extending portion 17 which is substantially centrally disposed with respect to the wear pad 16 and having a transverse forward portion 18. Where the longitudinally extending por-

tion 17 joins the transversely extending portion 18 it is offset somewhat toward the knuckle side of the coupler head, as at 19 to afford clearance for a link 20 which is movably connected to the lower end of the coupler lock 2 for the purpose of causing an unlocking operation of the latter. The wear pad 16 at the base of the coupler support 3 is preferably braced and reinforced by vertical transversely extending flanges 21 and 22 respectively. The wear pad 16 is also preferably braced by longitudinally extending flanges 23 and 24 respectively, the former preferably being in alignment with and forming a continuation of the web or plate-like portion 17 and the latter being spaced outwardly from said web portion toward the knuckle side of the coupler head. The reinforcing flanges 21, 22, 23 and 24 are preferably in the form of triangular gussets; and the flanges 21 and 22 are preferably not in transverse alignment as by so disposing them danger of shrinkage cracks in the casting is minimized.

The vertically extending plate portion 17 of the coupler support is provided with a circular opening 25 which communicates at its upper side with a radial slot 26. The circular opening 25 forms a bearing for the rotatable lock operating member 27, while the offset slot 26 permits the passage of a key 28 with which the rotatable member 27 is integrally provided. Extending downwardly from the underside of the coupler head in spaced parallel relation to the longitudinally extending plate portion 17 of the coupler support is a lug 29 having a circular opening 30 forming a bearing for the end of the shaft portion 31 of the rotatably uncoupling member 27. Disposed between the web 17 and the depending bearing lug 29 and integrally united to each is an arcuate lug 32 which serves to prevent the lifter arm 33 of the coupler release mechanism from becoming accidentally disassociated from the rotatable lock operating member 27 when the several parts of the lock operating device are in working relation. To avoid the necessity of unduly lengthening the coupler support 3, while at the same time permitting the lifter arm 33 to be assembled with or disassembled from the rotatable lock operating member 27 without the necessity of impairing the strength of the wear pad 16, said pad is preferably recessed or apertured between its ends, as at 34, to permit the lifter arm 33 to swing to a position where it will clear the arcuate lug 32 in the act of being assembled with or disconnected from the rotatable lock operating member 27. When the lifter arm 33 has been assembled with the rotatable member 27, as shown in Figure 5, the link 20 may be placed in position to form an operating connection between the arm 33 and the coupler lock 2, as shown in Figure 4.

The modified form of construction shown in Figure 7 illustrates the application of the invention to a short shank pilot coupler which is pivotally connected to a pocket flange casting 35 by a pivot pin 36. In this instance, 5 the coupler carrier 37 is shown as unprovided with a wear shoe for cooperating with the pad at the bottom of the coupler support 3 and the movable elements 20, 27 and 33 of the release mechanism by which the coupler lock 10 is actuated have not been illustrated although, of course, it will be understood that such are employed. Other features of the construction shown in Figure 7, being identical with those heretofore described, are indicated by corresponding reference numerals. 15

The construction and mode of operation of the movable parts of the coupler release mechanism are described in Letters Patent of 20 E. P. Kinne, No. 1,639,300, granted August 16, 1927 and, therefore, require no further description herein.

I claim:

1. In a railway draft appliance, the combination with a car coupler having a head and a bottom operating lock, of a coupler carrier mounted upon a railway vehicle and extending under said head, the latter being provided with a rigidly attached coupler support 25 extending downwardly therefrom and slidably supported by said carrier, and means extending under said head and movably mounted on said coupler support for actuating said lock.

2. In a railway draft appliance, the combination with a car coupler having a head and a bottom operating lock, of a coupler carrier mounted upon a railway vehicle and extending under said head in spaced relation thereto, a coupler support interposed between said head and carrier and slidably supported by the latter, said coupler support being movable with said head, and means movably mounted on said coupler support for actuating said lock.

3. In a railway draft appliance, the combination with a car coupler having a head and a bottom operating lock, of a coupler carrier 50 mounted upon a railway vehicle and extending under said head in spaced relation thereto, said head being integrally connected to a coupler support slidably engaging the coupler carrier, a member rotatably mounted on said coupler support, a lifter arm adapted to be actuated by said rotatably mounted member, and a link movably connected to said lifter and lock for actuating the latter.

4. In a railway draft appliance, the combination with a car coupler having a head, a bottom operating lock, and means extending under said head for operating the lock, of a coupler carrier mounted upon a railway vehicle and extending under said head in 55 spaced relation thereto, said head having in-

tegrally attached thereto a coupler support slidably engaging the carrier, said support being formed at its lower end with a wear pad for engaging the carrier and having a web portion extending upwardly from said pad, said web being disposed substantially central of said pad and extending longitudinally of the coupler, and said lock operating means overlapping said web transversely of the coupler.

5. In a railway draft appliance, the combination with a car coupler having a head and a bottom operating lock, of a coupler carrier mounted upon a railway vehicle and extending under said head in spaced relation thereto, a coupler support rigidly attached to said head and extending downwardly therefrom and slidably engaging the carrier, and a device extending under said head and movably mounted on said coupler support for actuating said lock, said coupler support being provided with bearing means permitting said lock actuating device to be rotatably mounted thereon and being formed at its lower end with a wear pad engaging the coupler carrier and being provided with bracing flanges extending upwardly from said pad at an angle to each other.

6. In a railway draft appliance, the combination with a car coupler having a head and a bottom operating lock, of a coupler carrier mounted upon a railway vehicle and extending under said head in spaced relation thereto, said head having rigidly attached thereto a coupler support extending downwardly therefrom and slidably supported by said carrier, said coupler support being provided at its lower end with a wear pad having a portion which projects rearwardly beyond said head.

7. In a railway draft appliance, the combination with a car coupler having a head and a bottom operating lock, of a coupler carrier mounted upon a railway vehicle and extending under said head in spaced relation thereto, a coupler support integrally attached to said head and extending downwardly therefrom and slidably supported by said carrier, and means extending under said head for actuating said lock, said means involving a rotatable member, and said coupler support being provided with a bearing for said rotatable member.

8. In a railway draft appliance, the combination with a car coupler having a head and a bottom operating lock, of a coupler carrier mounted upon a railway vehicle and extending under said head in spaced relation thereto, a coupler support rigidly attached to the head and extending downwardly therefrom and slidably engaging said carrier, and means extending under said head and movably mounted on the coupler support for actuating the said lock, said means comprising a rotatable shaft member, a lifter

- member actuated by said shaft member and a link member movably connecting said lifter member to the coupler lock, and said coupler support being provided with a wear pad for
- 5 cooperating with the coupler carrier and having a longitudinally extending plate-like portion connecting said pad to the coupler head, said plate-like portion being formed with an opening for receiving and forming
- 10 a bearing for said rotatable member.
9. In a railway draft appliance, the combination with a car coupler having a head and a bottom operating lock, a coupler carrier mounted upon a railway vehicle and extending
- 5 under said head in spaced relation thereto, means extending under said head for actuating said lock, said means including a rotatable shaft member, a lifter member actuated by said shaft member and a link member
- 20 operatively connecting the lifter member to said lock, a coupler support rigidly connected to the coupler head and extending downwardly therefrom, said support being provided at its lower end with a wear pad slidably sup-
- 25 ported by said carrier and having a longitudinally extending plate-like portion disposed above said pad, said plate-like portion having an opening forming a bearing for said rotatable member, said pad being
- 30 recessed to afford clearance for a portion of said lifter member, and a lug spaced laterally from said plate-like portion and formed with an opening providing a bearing for said rotatable shaft member.
10. In a railway draft appliance, the combination with a car coupler having a head and a bottom operating lock, of a coupler carrier mounted upon a railway vehicle and extending under said head in spaced relation
- 40 thereto, a coupler support integrally united to said head and extending downwardly therefrom and slidably supported by said carrier, and means extending under said head and movably mounted on said coupler sup-
- 45 port for actuating the lock, said means including a shaft member rotatably mounted on the coupler support, a lifter arm actuated by the shaft member, and a link member for connecting the lifter member to said lock,
- 50 said coupler support having at its lower end a horizontally extending wear pad for engaging the coupler carrier and having a vertically extending plate-like portion formed with an opening providing a bearing for said rotatable member, said plate-like portion being
- 55 offset to provide clearance for said lifter member.

In testimony whereof I affix my signature.
ENOCH GEORGE, JR.
